UTILITY POLE

James R. Baccanti, 3230 Santa Monica,
Fullerton, Calif. 92632

Filed May 21, 1968, Ser. No. 12,025

Term of patent 14 years

U.S. Cl. D26—12
Int. Cl. D13—03

FIG. 1 is a perspective view of a utility pole showing my new design;

FIG. 2 is a side elevational view;

FIG. 3 is a side elevational view taken at right angles relative to the view of FIG. 2; and

FIG. 4 is an enlarged top plan view thereof.

I claim:

The ornamental design for a utility pole, as shown.
